UNITED STATES PATENT OFFICE.

GEORGE A. GAUTHIER, OF HARTFORD, CONNECTICUT, ASSIGNOR TO THE ARROW ELECTRIC COMPANY, OF HARTFORD, CONNECTICUT, A CORPORATION OF CONNECTICUT.

SHADE-HOLDER.

1,156,473.

Specification of Letters Patent.

Patented Oct. 12, 1915.

Application filed June 12, 1914. Serial No. 844,624.

To all whom it may concern:

Be it known that I, GEORGE A. GAUTHIER, a citizen of the United States, residing at Hartford, in the county of Hartford and 5 State of Connecticut, have invented a new and useful Improvement in Shade-Holders, of which the following is a specification.

This invention relates to a structure which is particularly adapted for use in trolley 10 and other electric railway cars in which there is considerable vibration and jar, for holding the shades that are employed to cover and diffuse the light from the lamps, although, of course, the structure is equally 15 serviceable for holding lamp shades in other places.

In electric cars, whether they run on high-ways or private roadbeds, the lamps and shades are subjected to hard service owing 20 to the vibration and jar incident to the motion of the cars and to the fact that it is necessary to frequently clean the shades and the lamps, which labor is usually performed by unskilled and possibly careless employees.

25 The object of this invention is to provide a simple, neat and strong holder which can be very easily manipulated for securely fastening the shade in service position or releasing the shade so that it may be taken 30 down for cleaning, and which cannot be left after the shade has been put up unless the holder is positively secured in such manner that the shade cannot possibly drop down and become broken or cause injury to any 35 person happening to be beneath. In attaining this end the base end of the shade is positively clamped between a strong and substantial part that extends within it and a part that is securely fastened thereon and 40 extends over the outside of the end of the shade. The part that extends within the shade is provided with means which are designed to firmly engage with a part that projects from the supporting base, which 45 means are positively held against disengagement by a sliding part that is arranged in such manner that it cannot be operated to lock the connecting means against disengagement until the parts are so engaged that 50 the shade cannot drop off.

Figure 1 of the accompanying drawings which illustrate the invention, shows a side view of the holder with the parts assembled and locked together as when holding a shade. 55 Fig. 2 shows a side view of the holder with

the shade member disengaged from the base member. Fig. 3 is a central vertical section of the holder and the upper end of a shade with the parts locked together as in use. Fig. 4 is a section of one side of the lower part of the hub of the base member and the upper part of the sleeve of the shade member. Fig. 5 is a side view of the hub of the base member. Fig. 6 is a plan of the shade member.

The drawings show the ordinary type of lamp connections 1 attached in the usual manner to a common form of porcelain base 2. The base member of the holder has a metallic shell 3 of suitable design to cover the base, with a downwardly projecting hub 4 which incloses the lamp connections, and a collar 5 which freely slides up and down the hub. In the hub are a number of slots 6 and above these openings are outwardly 75 extending lips 7. The lips may be formed by striking the metal out from the slots and they act to prevent the collar from dropping from the hub, also to properly locate the shade member when it is applied to the base 80 member.

The shade member consists of a sleeve 8 that is larger at the bottom 8' than the opening in the base of the shade 9. This sleeve is thrust upward through the shade so that 85 its upper end projects some distance beyond. On the lower end of the sleeve and between it and the inner wall of the shade it is desirable to place a packing ring 10 of some soft material for the purpose of cushioning the 90 engagement. In slots in the sleeve are a number of spring arms 11, the upper ends of which are bent inward and are designed to enter the slots in the hub of the base member of the holder when the parts are assembled for use. Screwed on the exterior of the shade sleeve is a cap 12 which is designed to be turned down against the end of the shade so as to securely fasten together the shade and the shade member. A packing 100 ring 13 may be placed in this cap so as to bear against the edge of the shade for cushioning the parts.

In assembling the members the sleeve is thrust up through the shade and the cap is 105 screwed on the sleeve until the edge of the shade is firmly clamped between the sleeve and cap. The shell with its hub is fastened over the base and the lamp connections. To put up the shade the sleeve which supports 110

it is thrust upwardly onto the hub of the base, which it closely fits, until the inturned ends of the spring arms on the sleeve are opposite the slots in the hub. Then when 5 the collar on the hub is drawn down the ends of the arms are forced into the slots. As long as this collar is down, and it cannot be drawn down until the ends of the spring 10 arms have entered the slots, the ends of the arms cannot work out of the slots and allow the shade to drop. In order to remove the shade the collar on the hub of the base member is pushed up. This releases the spring arms so that the shade will drop free and 15 may be removed for cleaning. A small annular groove 14 is made in the inner wall of the collar so that the ends of the spring arms, which have a slight outward bend as well as an inward bend, will enter this 20 groove and prevent the collar from accidentally moving upward and releasing the arms so that they can disengage from the slots in the hub. The sleeve which holds the shade cannot be pushed up on the hub 25 until the lips on the hub enter the slots in the sleeve which contain the spring arms and the parts are in proper relative positions for the spring arms to engage the slots in the hub, and the collar which locks 30 the spring arms cannot be drawn down without forcing the ends of the arms into the slots. Thus while the shade can be easily and quickly removed by proper manipulation it cannot accidentally drop after it 35 has been once put up. If it is improperly put up it will drop before the attendant leaves as there is nothing to hold it until the locking sleeve is drawn down which, as stated, cannot be done until the parts are in 40 proper positions to be locked.

With this construction the shade cannot drop off as a result of any chipping or breaking of the rim around its base, and it cannot be left until it is positively locked 45 in a safe position and it cannot become unlocked by any vibration, shaking or shock to the parts. For this reason the holder, as previously pointed out, is particularly serviceable for electric car service. The holder 50 may be made for all sizes of shades although it is especially serviceable for shades which are large and heavy.

The invention claimed is:

1. A shade holder comprising a supporting member, a shade holding member independent of but having its upper end fitting and adapted to be slid longitudinally upon the supporting member, fingers on the shade member normally out of engagement with 55 but adapted to be engaged with parts of the supporting member, and a collar adapted to be slid longitudinally onto the shade mem-

ber into contact with the fingers and force them out of normal position into engagement with the supporting member so as to 65 detachably lock said supporting and shade holding members together.

2. A shade holder having a base member, a slotted hub projecting from the base member, a shade member with its upper end 70 fitted onto said hub, fingers on the shade member and having their ends normally out of engagement with but adapted to be engaged with walls of the slots in said hub, and a collar fitting and sliding longitudinally 75 on the hub and the upper part of the shade member into contact with the fingers and force the ends of the fingers into the slots in the hub.

3. A holder having a base member with a 80 slotted hub, a shade member adapted to fit said hub, means for securing a shade to said shade member, spring arms carried by the shade member and adapted to engage the slots in the hub of the base member, and a 85 collar sliding on the hub of the base member and adapted to hold the spring arms in the slots in the hub of the base member and said collar having means whereby it is held by 90 said spring arms from accidental movement. 90

4. A shade holder having a supporting member with a hub projecting therefrom, a shade member fitting said hub and having means for engaging the inside of a shade, a cap 95 screwed on the shade member and co-operating with said means thereon for securing a shade thereto, fingers on the shade member normally out of engagement with but adapted to be forced into engagement with the supporting member, and a collar 100 fitting said members and adapted to slide longitudinally thereon into contact with the fingers and force them out of normal position and into engagement with the supporting member so as to lock the members together. 105

5. A shade holder having a base member with a hub projecting therefrom, a shade member fitting said hub and having means for engaging the inside of a shade, a cap 110 screwed on the shade member and co-operating with said means thereon for securing a shade thereto, spring fingers to connect the members, said fingers being normally out of engaging position, and a collar fitting said members and adapted to slide longitudinally thereon into contact with the fingers and force them out of normal position and into engaging position so as to lock the members together. 115
